[57] CLAIM

The ornamental design for trimaran boat with human-powered propeller drive, as shown and described.

DESCRIPTION

FIG. 1 is a right side elevational view of a trimaran boat with human-powered propeller drive showing my new design, the left side elevational view being a mirror image of that shown;

FIG. 2 is a top plan view thereof;

FIG. 3 is a bottom plan view thereof;

FIG. 4 is a front elevational view thereof;

FIG. 5 is a rear elevational view thereof; and,

FIG. 6 is a top perspective view thereof.
